(57) **CLAIM**

The ornamental design for a multi-positional clip accessory, as shown and described.

DESCRIPTION

FIG. 1 is a front perspective view of a multi-positional clip accessory showing my new design in an environment of use; FIG. 2 is a front perspective view of the multi-positional clip accessory of FIG. 1, shown in a first position; FIG. 3 is a front perspective view of the multi-positional clip accessory of FIG. 1, shown in a second position; FIG. 4 is a front elevational view of the multi-positional clip accessory of FIG. 1, shown in a first position; FIG. 5 is a rear elevational view thereof; FIG. 6 is a top plan view thereof; FIG. 7 is a bottom plan view thereof; FIG. 8 is a left side elevational view thereof; and, FIG. 9 is a right side elevational view thereof. Broken lines showing a cellular phone in FIG. 1 illustrate environment and form no part of the claimed design.
